CLAIM

The ornamental design for a window thermometer having a cylindrical body and cone-like top, as shown and described.

DESCRIPTION

FIG. 1 is a perspective view of a window thermometer having a cylindrical body and cone-like top showing my new design;

FIG. 2 is a perspective view similar to FIG. 1, and illustrating a mounting bracket therefor in an opposite position;

FIG. 3 is a front elevational view of the thermometer shown in FIG. 1;

FIG. 4 is a right side elevational view of the thermometer shown in FIG. 1; and,

FIG. 5 is a top plan view of the thermometer shown in FIG. 1.
